MARTIN ERNEST FEILMANN, DONALD BAGLEY, AND ARTHUR HERBERT SMITH, OF LONDON, ENGLAND.

APPARATUS FOR PURIFYING BLAST-FURNACE GASES.

1,216,677.

Specification of Letters Patent. Patented Feb. 20, 1917.

Application filed May 1, 1914. Serial No. 835,761

To all whom it may concern:

Be it known that we, MARTIN ERNEST FEILMANN, of 92 Victoria street, Westminster, London, S. W., England, and DONALD BAGLEY and ARTHUR HERBERT SMITH, of Broad Street House, London, E. C., England, have invented new and useful Improvements in Apparatus for Purifying Blast-Furnace Gases, of which the following is a specification.

This invention has for its object the removal of solid matter such as particles of metallic iron, gangue, coke or other fuel more particularly and generally described as dust from blast furnace gases or from gases issuing from other similar types of furnace. The impurities referred to are objectionable when the gases are used for heating stoves, firing boilers, or for heating purposes generally, and particularly when it is desired to utilize the gases for the generation of power in internal combustion engines.

The system claimed by us overcomes the disadvantages inherent in those hitherto used for such gases, as it is perfectly continuous and makes use of revolving filtering bands. Continuous revolving bands have already been proposed for the removal of dust from air by filtration in conjunction with a vacuum extractor to remove the filtered dust from the bands, but the novelty which we claim consists in the passage of the bands through the walls of the casing or flue to the outside, and the application of a vacuum extractor to remove the dust outside the casing or flue, whereas in the arrangements hitherto described the textile band circulates entirely inside the casing or flue and the vacuum extractor is therefore necessarily applied inside. This is of no consequence in the case of the purification of air, but is highly disadvantageous in the case of a valuable gas such as blast furnace gas, as it would lead to loss of large quantities of such gas which would be removed by the vacuum extractor. The novel arrangement which we now claim is therefore as follows:—

In the application of the process to blast furnace gas, the gases, after passing through a dust extractor of the usual type, which removes very coarse particles of solid matter, are cooled to a suitable temperature, which may be that of the outside atmosphere, and are then passed into a special dust filter. This consists of a casing of metal or

other material, through the interior of which bands, which may be endless, of textile material continuously circulate, traveling in a direction at right angles to the length of the casing and so arranged that the whole of the gas traversing the casing is forced to pass through the fabric, by which means the gases are deprived of the dust which they contain in suspension. The movement of the fabric is effected by means of rollers outside the casing or by other suitable means and it enters and leaves the casing through slots so arranged that they are practically gas-tight. The gas may be passed through any number of successive layers of moving fabric according to the amount and character of the dust and the degree of purification desired. The interior of the casing is provided with means for imparting heat to the fabric so that it is retained in a dry condition. The dust which is continuously removed to the outside of the casing by the moving fabric is there removed continuously from the fabric by means of the vacuum extractors. Each of these consists of a metal casing provided with a slot which is pressed against the whole width of the band of fabric. By means of a constant vacuum maintained within this casing with the aid of a pump or fan the dust is continuously removed and passed into a suitable receptacle. Before the fabric is submitted to the action of the vacuum any magnetic dust particles may be separately removed by means of a magnetic separator so placed that it acts on the dust within the fabric before it passes under the action of the vacuum extractor. The clean fabric then passes back into the casing where its functions are maintained with undiminished power and the dust particles are again removed subsequently. A series of these bands can be operated by one motor. The clean gases may be further cooled by an indirect cooler of the tubular kind. Motion is, or may be, imparted to the gases by any suitable form of exhauster or blower at any convenient stage of the process.

The attached drawing shows one method of carrying out the said invention. The gases pass from the ordinary dust extractor and coolers into the casing "B" at "A", moving in the direction of the arrows. They then pass forward and the dust which they contain is filtered out by the band of

2

textile material "C", which travels in the direction of the arrows and is actuated by the rollers "G". The gases pass out of the apparatus at "H" to the cooler and storage holder. The magnetic separators are indicated diagrammatically at "M" and the vacuum extractors at "V". "K" indicates the position of heating pipes for maintaining the textile fabric in a dry condition and these pipes may be heated by a diverted current of hot furnace gas or in any other suitable manner.

We claim:—

1. In an apparatus for purifying blast furnace gas or other similar gases, the combination of a closed casing having inlet and outlet openings for the gases passing to and from said casing, traveling bands or tapes moving within the casing for collecting dust or other matter from said gases, and means coöoperating with the bands outside the casing for removing such collected matter.
2. In an apparatus for purifying blast furnace gas or other similar gases, the combination of a closed casing having inlet and outlet openings for the gases passing to and from said casing, traveling bands or tapes entering said casing through slots in the side thereof, said bands or tapes moving within the casing in a direction approximately at right angles to the flow of gases passing through said casing, and means outside the casing for removing the dust or other matter collected by the bands.
3. In an apparatus for purifying blast furnace gas or other similar gases, the combination of a closed casing having inlet and outlet openings for the gases passing to and from said casing, traveling bands or tapes entering said casing through slots in the side thereof, said bands or tapes moving within the casing in a direction approximately at right angles to the flow of gases passing through said casing, and a vacuum extractor located outside the casing and co-operating with the bands for removing the dust collected thereby.
4. In an apparatus for purifying blast

furnace gas or other similar gases, the combination of a closed casing having inlet and outlet openings for the gases passing to and from said casing, traveling bands or tapes entering said casing through slots in the side thereof, said bands or tapes moving within the casing in a direction approximately at right angles to the flow of gases passing through said casing, a vacuum extractor located outside the casing and co-operating with the bands for removing the dust collected thereby, and a magnetic separator for extracting metallic particles from the collecting bands prior to the operation of the vacuum apparatus.

5. In an apparatus for purifying blast furnace gas or other similar gases, the combination of a closed casing having inlet and outlet openings for the gases passing to and from said casing, said casing having slots in its side walls, an endless band passing through said slots and traveling in a direction at right angles to the direction of flow of the gases through the casing, rollers or pulleys journaled outside the said casing over which the bands are adapted to travel for actuating the same, and means for removing the dust or other matter collected by said bands.

6. In an apparatus for purifying blast furnace gas or other similar gases, the combination of a closed casing having inlet and outlet openings for the gases passing to and from said casing, traveling bands or tapes of textile material moving within the casing, in a direction at right angles to the direction of flow of the gases through said casing, heating devices within said casing for maintaining the textile bands in a dry condition, and means for removing the dust or other matter collected by said bands.

Dated this eighteenth day of April, 1914. 90
